UNITED STATES PATENT OFFICE.

FRED STEINKAMP, OF BETHANY, CALIFORNIA.

BICYCLE-GEARING.

SPECIFICATION forming part of Letters Patent No. 716,129, dated December 16, 1902.

Application filed August 2, 1902. Serial No. 118,113. (No model.)

To all whom it may concern:

Be it known that I, FRED STEINKAMP, a citizen of the United States, residing at Bethany, in the county of San Joaquin and State of California, have invented a new and useful 5 Bicycle-Gearing, of which the following is a specification.

This invention relates generally to bicycle-gearing, and more particularly to a changeable gearing by means of which speed of a bicycle can be regulated, it being desirable to obtain an increase of speed upon level and good roads and a corresponding increase in power and decrease in speed upon steep or 15 bad roads.

The object of the invention is to provide an exceedingly cheap, simple, and efficient means for accomplishing this variation in speed without removing any nuts or bolts or 20 without making any change in the drive-chains except to shift the said chain from one side of said sprockets to another.

The invention consists also in the novel features of construction and combination, all of 25 which will be fully described hereinafter and pointed out in the claims.

In the drawings forming part of this specification, Figure 1 is a side elevation illustrating the crank-hanger and drive-sprockets constructed and arranged in accordance with my 30 invention. Fig. 2 is a horizontal sectional view taken through the crank-hanger and showing the novel manner of journaling the crank-shaft therein. Fig. 3 is a vertical sectional view showing the eccentric arrangement of the crank-shaft within the crank-hanger. Fig. 4 is a side elevation showing the cylinder shifted so as to throw the crank-hanger to its rearmost position. Fig. 5 is a 35 detail perspective view of the catch. Fig. 6 is a detail perspective view showing the end of the lever. Fig. 7 is a detail view showing the head of the cylinder and the lever connected thereto. Fig. 8 is a detail perspective view of the cylinder.

In carrying out my invention I employ a crank-hanger A, which is connected to the bicycle-frame in the usual manner, and fitting snugly within the said crank-hanger is 40 a cylinder B, the heads B' of which have openings B² produced eccentrically therein,

and secured in the said eccentric openings is the sleeve C, in which the crank-shaft D is journaled. The bearing-sleeve C may be composed of any desirable number of parts provided with the usual ball-bearing devices. 55

A sprocket E is mounted upon the crank-shaft D, said sprocket being a double sprocket, one toothed rim E' being larger than the other toothed rim E², and consequently provided with a larger number of teeth, the larger rim being employed when speed is desirable and the smaller rim being employed when power is desired more than speed. The sprocket F upon the rear axle is also double, 60 the smaller one, F', being adapted for use in connection with the larger sprocket-rim of the wheel E, while the larger one, F², is adapted for use in connection with the smaller rim E² of the sprocket E, it being understood that 65 the diameters of said sprockets are such that one chain can be used upon both sets of sprockets without making any changes or alterations in the said chain. In order to slacken the chain, so as to shift it from one set 70 of sprockets to another, I propose to move the crank-shaft rearwardly, and in order to do this it is only necessary to turn the cylinder in the crank-hanger, inasmuch as the sleeve carrying the crank-shaft is eccentrically arranged in the said sleeve B. In order to accomplish this movement of the cylinder, I provide a lever G, which is rigidly connected to one of the cylinder-heads and is provided with a spring-actuated latch G' at its 75 free end which is adapted to engage a catch G², depending from the rear horizontal member of the frame. A suitable guide-finger G³ is arranged parallel with the catch for the purpose of guiding and holding the lever and 80 its spring-latch in connection with the catch. When the lever is held in engagement with the catch, the crank-shaft will be held to its 85 foremost position, and consequently the drive-chain will be held taut, and when it is desired to slacken the chain the lever is disengaged from the catch and moved around to its position shown in Fig. 4, thus shifting the crank-shaft, and with it the sprocket E, to their lowermost position, and at each time 90 the chain can be readily transferred from one set of sprockets to the other. After the chain 95

has been adjusted the lever is turned back, carrying with it the cylinder, and consequently the crank-shaft and sprocket.

It will thus be seen that I provide an exceedingly cheap, simple, and efficient construction, whereby a variable-speed driving-gear is produced, and one in which the variation can be accomplished without removing any bolts or nuts or without making any change in the drive-chain.

Having thus fully described my invention, what I claim as new, and desire to secure by Letters Patent, is—

1. The combination with a crank-hanger, of a cylinder mounted to turn therein, the crank-shaft journaled eccentrically in the said cylinder, a lever connected to the said cylinder whereby the cylinder is turned, and a catch adapted to engage and hold the lever in a locked position for the purpose specified.

2. The combination with a crank-hanger, of a cylinder adapted to turn therein, a sleeve arranged eccentrically in the cylinder, the crank-shaft journaled in the said sleeve, a

double sprocket mounted on the crank-shaft, a double sprocket mounted upon the rear axle, the drive-chain connecting the said sprockets, the lever connected to one end of the cylinder, a spring-actuated latch carried by the said lever and the catch arranged upon the bicycle-frame and adapted to engage the lever for the purpose specified.

3. The combination with a bicycle, of a crank-hanger, of a cylinder mounted to turn therein, a crank-shaft journaled eccentrically therein, a double sprocket mounted on the crank-shaft, a double sprocket mounted on the rear axle, an end piece adapted to be secured to the cylinder, an arm integral with the end piece adapted to revolve the cylinder where the position of the arm is changed and means for locking the free end of the arm to the frame of the bicycle.

FRED STEINKAMP.
